UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

ELECTRICAL CONNECTOR DEVICE.

1,422,170.

Specification of Letters Patent. Patented July 11, 1922.

Application filed December 19, 1917. Serial No. 207,641.

To all whom it may concern:

Be it known that I, REUBEN B. BENJAMIN, a citizen of the United States, residing at Chicago, in the county of Cook and State 5 of Illinois, have invented new and useful Improvements in Electrical Connector Devices, of which the following is a full, clear, concise, and exact description, reference being had to the accompanying drawing, forming 10 a part of this specification.

My invention relates to electrical connector devices, and, more specifically, to pull switch receptacles.

One of the objects of my invention is to 15 provide an improved receptacle of the type in which the cap and shell of the casing are formed integral with each other, with a switch for controlling the circuit through the receptacle contacts. A further object is 20 to provide such a receptacle which will be simple in construction and efficient in operation, easy to assemble and cheap to manufacture. Further objects will appear from the detailed description to follow and from 25 the appended claims.

In the drawings illustrating my invention—

Fig. 1 is a side elevation of a pull switch receptacle or socket embodying my invention; 30

Fig. 2 is a section on the line 2—2 of Figs. 1 and 3;

Fig. 3 is a section substantially on the line 3—3 of Fig. 2;

Fig. 4 is a section on the line 4—4 of Fig. 3;

Fig. 5 is a section on the line 5—5 of Fig. 2;

Fig. 6 is a section on the line 6—6 of Fig. 5;

Fig. 7 is a section on the line 7—7 of Fig. 2;

Fig. 8 is a section on the line 8—8 of Fig. 3;

Fig. 9 is a section on the line 9—9 of Fig. 5;

Fig. 10 is a section on the line 10—10 of Fig. 9;

Fig. 11 is a view looking into the open 50 end of the receptacle;

Fig. 12 is a fragmentary side view of the insulating base which carries the receptacle contacts;

Fig. 13 is a section on the line 13—13 of Fig. 1;

Fig. 14 is a sectional view showing another form of securing one of the contacts; and Fig. 15 is a side elevation of the switch lever and pawl.

Referring to the drawings in detail, the 60 receptacle shown comprises an insulating base 20, shell and center contacts 21 and 22, respectively, supported by said insulating base, quick detachable contacts 23 and 24, also supported by the insulating base 20, a 65 second insulating base 25, combined binding plates and quick detachable contact members 26 and 27 supported by the insulating base 25, switch mechanism 28 supported between the insulating bases 20 and 25, a casing 28^a 70 for housing the insulating bases and associated parts, a retaining ring 29 threaded into the lower end of the casing 28^a for holding the insulating bases 20 and 25 in position in the casing, and an internally 75 threaded bushing 30 secured at the upper end of the casing 28^a for screwing onto the threaded end of a conduit.

The threaded shell contact 21 is electrically connected with the quick detachable 80 contact 23 by means of a screw 31, which also serves to hold the quick-detachable contact 23 in place and assists in holding the shell contact in place. The switch mechanism 28 shown in axial section in Fig. 5 com-

85 prises a central shaft 32, an insulating member 33 rotatably mounted on the shaft 32, a brush or contact member 34 mounted on the insulating member 33, two U-shaped leaf spring contact members 35 and 36, respectively, for co-operation with the contact member 34, a switch lever member 37 to which the pull chain 38 is attached, a pawl 39 for transmitting motion from the lever 37 to the insulating member 33, and a spring 90 40 surrounding the shaft 32 and located in an axial recess in the insulating member 33 for returning the lever 37 after it has been actuated by pulling down on the pull chain 38.

100 The spring contact 35 is electrically connected with the center contact 22 by means of a screw 41 (Fig. 2) threaded into a nut 42, said screw and nut also serving to hold the spring contact 35 and center contact 22 105 in position on the insulating base 20. A

strip of insulation 43, such as mica or the like, is located between the center contact 22 and the flange 44 of the shell contact 21 to prevent short circuiting. The flange 44 5 has an enlarged opening 45 through which the screw 41 extends, the diameter of the opening being greater than the diameter of the screw, to prevent short circuiting.

The spring contact 36 and the quick detachable contact 24 are held in place on the base 20 and in engagement with each other by means of a screw 45, which extends through an opening in the spring contact 36 and is threaded into the quick detachable 10 contact 24 (Fig. 2). This screw 45 also serves to assist in holding the shell contact 21 in place, the flange 44 of the shell contact being provided with an opening 46 through which the screw 45 extends, the diameter of the opening 46 being larger than the shank 20 of the screw, to prevent short circuiting, and a washer 47 of insulating material, such as mica or the like, being provided between the head of the screw 45 and the flange 46 to 25 prevent short circuiting. A washer 48 may be provided between the head of the screw 45 and the insulating sheet 47.

The contact member 34 alternately makes and breaks the electrical connection between the spring contacts 35 and 36. The lever 37 30 may be a sheet metal stamping comprising a portion 49, a portion 50 lying substantially in a radial plane through the axis of the shaft 32, and an arcuate flange portion 51 35 forming a bearing portion for the pull chain 38. For attaching the pull chain 38, a circular opening 52 is provided in the portion 49, large enough to permit the passage of one of the balls 53 of the pull chain 38, and a 40 restricted slot 54 leads from this circular opening 52 to the portion 50, this restricted slot being large enough to permit the passage of the connection 55 between the balls 53 of the chain, but not large enough to permit the passage of the balls 53.

A retaining lug 56 is provided to prevent the pull chain from slipping off the bearing portion 51. The pawl 39 may be a sheet metal stamping, and has a hook-shaped portion 57 extending through a slot 58 in the lever 37, the slot 58 extending substantially parallel to the axis of the shaft 32. The point of the pawl 39 engages the teeth of a ratchet 59 formed on a portion of the insulating member 33. The pawl 39 is provided with an outwardly-extending hump or projection 60, on which one of the balls 53 bears to hold the pawl in proper relation with respect to the ratchet teeth 59.

60 A cup-shaped sheet metal stamping 61 serves to connect the coil spring 40 and the switch lever 37. This cup-shaped member is secured to the portion 49 of the switch lever at 62 in any suitable manner, as by extending 65 a portion of the switch lever through an

opening in the cup-shaped member and riveting it.

One end 63 of the coil spring may be connected to the cup-shaped member 61 by extending through an opening in the cup-shaped member, and the other end 64 of the coil spring may extend into a recess in the insulating base 20 to hold this end of the spring against movement.

The insulating member 33 may be provided with a flange portion 65 to prevent the chain 38 and pawl 39 from coming into contact with the brush 34 and contacts 35 and 36. The contact member 34 comprises two brush or contact portions 66 and 67 for contact with the spring contacts 35 and 36, and a central connecting and conducting portion 68 extending between the contact portions 66 and 67 and formed integral therewith. The contact member 34 may be a sheet metal 85 stamping.

The combined binding plate and contact member 26 may be substantially the same in construction. Each comprises a substantially flat binding plate portion 69 (Figs. 9 and 10) and a flexible contact portion 70 for engagement with the quick-detachable contact plates 23 and 24. The members 26 and 27 may be secured to the insulating base 25 by means of rivet members 71, which may be 95 sheet metal stampings having projections 72 extending through openings in the members 26 and 27 and riveted over as indicated in Fig. 10. Suitable binding screws 73 are provided, which extend through openings in 100 the binding plate portions 69 and are threaded into nuts 74 located in recesses in the insulating base. The flexible contact portion 70 and the head of the binding screw 73 are located on opposite sides of the plane of the 105 binding plate portion 69. An opening 75 is provided in the insulating base 25, through which the feed wires are led to the binding screws 73. The insulating bases 20 and 25 are provided with suitable recesses 76 and 110 77 to accommodate the switch mechanism 28.

The casing 28^a may be a single integral piece of formed sheet metal having its lower end rolled to form a thread 78 for engagement with the threaded portion 79 of the retaining ring 29, which retaining ring may also be formed of a single piece of sheet metal.

The upper portion of the casing 28^a is reduced and polygonal in cross section (Fig. 120 6), and the internally threaded bushing 30 is also polygonal in cross section and fits snugly in the reduced portion 80 of the casing. The exterior of the bushing 30 is turned down at one portion to substantially 125 circular cross section, as indicated at 81, and the polygonal portion 80 is rolled down as indicated at 82, until it is substantially circular in cross section to fit into the groove formed at 81. The casing member 28^a may 130

be flanged over the upper edge of the bushing 30, as indicated at 83.

The insulating base 20 is provided with a suitable passage 83^a for the pull chain 38.

5 If desired, suitable lamp-gripping means may be provided, comprising a U-shaped spring member 83^b embracing the threaded shell contact 21 and having portions extending through slots in the side of the shell for 10 engagement with the lamp base.

In Fig. 14 I have shown another form of securing the binding plate and contact members 26 and 27 to the insulating base 25. In this form an internally threaded metal bushing 83^c is imbedded in the base 25, and the 15 binding screw 73 extends through an opening in the binding plate and contact member 26 and is threaded into the metal bushing 83^c, the metal bushing being flanged 20 over as indicated at 83^d to hold the binding plate and contact member in position on the base 25.

In wiring the device, the retaining ring 29 is unscrewed from the casing 28^a and the 25 insulating bases 20 and 25 are removed from the casing. The bushing 30 is then slipped over the feed wires and screwed onto the end of the conduit. The feed wires are then inserted through the opening 75 in the insulating base 25 and secured beneath the 30 heads of the binding screws 73, respectively. The two insulating bases 20 and 25 are then brought into proper position with respect to each other and the contacts 23 and 24 are 35 brought into engagement with the quick detachable contact members 26 and 27, respectively. The two bases are then inserted in the casing 28^a and the retaining ring 29 is screwed into place.

40 For positioning the insulating base 25 with respect to the casing 28^a, the casing may be brought inwardly to provide depressions 84 for engagement with corresponding depressions in the insulating base 45 25.

The circuit is from the combined binding terminal and contact member 27 to the contact member 24, spring contact 36, switch contact member 34, spring contact 35, screw 50 41, center contact 22, translating device, shell contact 21, screw 31, and contact member 23 to the combined binding terminal and contact member 26.

The operation of the switch mechanism 55 is as follows: Assuming that the switch mechanism is in the position shown in Fig. 4, the chain 38 is pulled downwardly to give the rotatable member 83 substantially a quarter of a revolution through the switch 60 lever 37 and pawl 39. This brings the contact portions 66 and 67 of the contact member 84 into engagement with the spring contacts 36 and 35, respectively, and completes the circuit between the binding terminal 65 27 and the center contact 22. When

the pull chain 38 is released the coil spring 40 returns the switch lever to its original position, the spring contacts 35 and 36, however, preventing the insulating member 33 from rotating back with the switch lever. 70 The return movement of the switch lever is limited by means of an abutment 85 on the insulating base 20, which engages a portion of the switch lever 37 to limit its movement. During the return movement of the switch 75 lever the pawl 39 rides over the ratchet 59, and the pawl 39 drops down into position to engage with the teeth of the ratchet.

I claim as new and desire to secure by Letters Patent of the United States: 80

1. A switch mechanism comprising a rotatable insulating member, a switch contact supported thereby, a lever and pawl for actuating said rotatable member, and a ball-chain connected with said lever, said lever 85 comprising a sheet-metal member having a portion lying in a plane substantially perpendicular to the axis of said rotatable member, and a portion lying in a plane substantially radially with respect to the axis of 90 said rotatable member, said first portion having an opening therein large enough to permit the passage of one of the balls of the ball-chain, there being a slot leading from said opening to said second portion, not 95 large enough to permit the passage of one of the balls but large enough to permit passage of the connection between the balls.

2. A switch mechanism comprising a rotatable insulating member, a switch contact supported thereby, and a lever and pawl for actuating said rotatable member, said lever comprising a sheet metal portion having a slot therein extending substantially parallel to the axis of said rotatable member, and said pawl comprising a sheet metal 100 spring member having a portion extending into said slot for connecting it to the lever.

3. A switch mechanism comprising a rotatable insulating member, a switch contact supported thereby, and a lever and pawl for actuating said rotatable member, said lever comprising a sheet metal portion having a slot therein extending substantially parallel to the axis of said rotatable member, and 110 said pawl comprising a sheet metal member having a hook portion inserted through said slot for connecting said pawl to said lever member.

4. A pull switch mechanism comprising a 120 movable contact member, a ratchet member for actuating said movable contact member, a pawl for actuating said ratchet member, and a chain for actuating said pawl, said chain bearing on said pawl for holding it in 125 proper engagement with said ratchet member.

5. A pull switch mechanism comprising a movable contact member, a ratchet member for actuating said movable member, a pawl 130

for actuating said ratchet member, and a flexible member for actuating said pawl, said flexible member bearing on said pawl for holding it in proper engagement with said ratchet member.

5 6. A switch mechanism comprising a shaft, a switch lever oscillatable about the axis of said shaft, a tubular member surrounding and coaxial with said shaft, and 10 secured to said switch lever, a commutator

surrounding said tubular member and having a bearing thereon, and rotatable about the axis of said shaft, and a spring, surrounding said shaft and surrounded by said tubular member, for returning said switch 15 lever.

In witness whereof, I have hereunto subscribed my name.

REUBEN B. BENJAMIN.
